SEWER CLEANING BUCKET FOR PASSING
AROUND SHEAVES

Lawrence R. Robinson, Mount Lebanon, Kyle I. Robinson, Glenshaw, Earl O. Berger, Bellevue, and Walter S. Lang, Pittsburgh, Pa., assignors to Pittsburgh Pipe Cleaner Company, Pittsburgh, Pa., a corporation of Pennsylvania

Application January 31, 1947, Serial No. 725,586

3 Claims. (Cl. 15—104.30)

1

This invention relates to sewer cleaners and, in particular, to sewer cleaning buckets.

In cleaning a sewer, the opposite ends of a bucket are connected to cables wound on power winches located beside the upper ends of a couple of manholes leading to the sewer. The cables drag the bucket back and forth in the sewer pipe until the bucket is filled, and then it is drawn out of the pipe around a sheave in the lower part of the manhole, pulled out of the manhole by one of the cables and emptied. However, the upper front edge of the sewer cleaning bucket occasionally catches on the sheave and jams, due to the bucket being led in close to the sheave. In that case, it is necessary for a workman to go down the manhole and free the bucket. This is a time consuming, unhealthy and undesirable job.

It is therefore an object of this invention to provide a sewer cleaning bucket with means to prevent the bucket from catching on the sheave and around which it is pulled up out of the sewer.

According to the invention, a pair of rearwardly diverging plates are mounted on the bail of a sewer cleaning bucket. The forward edge of each plate is connected to the central portion of the bail, and the rear edge is of sufficient length that its outer ends lie adjacent to the bail, this latter edge being curved outwardly between its ends. As the bail is being dragged up around the manhole sheave by the cable, one or the other of the plates will engage the sheave and push the bail away from it. Then, as the cable continues its pull, the plate operates as a fulcrum on which the bail rocks to depress the front end of the bucket a sufficient amount to prevent it from catching on the sheave.

The preferred embodiment of the invention is illustrated in the accompanying drawings, of which Fig. 1 is a vertical section of a portion of a sewer illustrating the sewer cleaning process for which the invention is adapted; Figs. 2, 3 and 4 are enlarged views similar to Fig. 1 showing the successive positions of the sewer cleaner as it is dragged around the sheave; Fig. 5 is a side view of the sewer cleaning bucket; Fig. 6 is a fragmentary plan view taken along lines VI—VI of Fig. 5; and Fig. 7 is a front end view of the bucket bail passing around the sheave.

Referring to Figs. 1, 5 and 6, a bucket which is most useful in this work has an open front end 1 and a rear end 2 formed of normally closed jaws 3. Bails 4 and 5 are connected pivotally to both ends of the bucket and are each provided at their center portions or outer ends with a plate 6 adapted to connect the bucket to cables 7 for

2

moving the bucket through the sewer. Normally, the bucket rides on runners 8 as it is moved. Jaws 3 are operatively connected in well known manner to the rear ends of a pair of side bars 9 that can slide lengthwise outside of the bucket side wall. The ends of bails 4 extend through the front ends of the side bars and through underlying longitudinal slots 11 in the bucket wall. When bail 4 is pulled by its cable, the side bars hold the jaws 10 closed. Bail 5 is attached to the rear ends of side bars 9 so that, when it is pulled, the jaws are swung open by the bars. In cleaning the sewer, one cable drags the bucket rearwardly in the pipe with the jaws open, and then the other cable drags the bucket in the opposite direction with its jaws closed so that it will become filled with mud and debris. The filled bucket then is pulled out of the sewer around a sheave 10 and into a manhole, from which it is hoisted clear and emptied.

The sheave preferably is provided with a support which is adjustable vertically at ground level so that workers need not descend into the manhole to position it. Such a support, shown in Fig. 1, comprises a forked frame 12 in which the sheave is rotatably mounted, the frame being secured to a guide post 13. The guide post is adjustably mounted in any suitable frame (not shown) positioned outside of the manhole.

One feature of this invention is that means 30 are mounted on the bail at the open or front end of the bucket to prevent the upper edge of this end from catching on the sheave and jamming. Such means comprise a pair of plates 20 mounted on opposite sides of the plane of the bail 4. Bail 4, as shown in Fig. 5, has inwardly projecting ends 16 attached to the bucket as described above, substantially straight sides 17, and an arcuate central portion 18 which forms the outer end of the bail. The plates are welded or otherwise secured to central portion 18 of the bail at their forward edges 19 and, accordingly, these edges are curved to conform to the curvature of this central portion. The rear edge 21 of each plate extends across the bail near the front end of its straight sides 17 and meets the opposite ends of the curved front edge of the plate at points connected to the bail. Thus, the plates engage, and are supported by, the bail except along their rear edges. Each plate is bowed outwardly lengthwise of its rear edge. A center line extending perpendicularly from the middle of the rear edge of the plate to its front edge preferably makes an angle of about 45° with the plane of the bail, as shown in Fig. 5.

The plates form a pair of arched shoulders for

the bail, the functions of which will be described in more detail later. However, the particular form illustrated and described may be varied considerably to conform to differently shaped or sized balls and, so long as the described functions remain, such variations are contemplated by this invention. These functions will be described with reference to Figs. 2, 3 and 4 which show some of the successive positions that may be assumed by the bucket as the front cable 7 pulls it up around sheave 10. Such positions may vary to some extent depending on the load in the bucket, the debris in the pipe or other conditions.

In Fig. 2, the bucket shown in full lines is seen as it approaches the sheave 10 immediately preceding any contact of plates 20 with the sheave. Since the bucket is adapted to ride on its runners 8, this is the normal approach position. However, if the approaching bucket has been rotated from its normal position, it will be returned to its normal position as soon as the bail strikes the sheave. Thus, as shown in broken lines, one or the other of plates 20 will come into engagement with the sheave as the bucket is pulled out of the sewer pipe.

The plate 20 that is riding around the sheave serves two useful purposes. In the first place, the plate pushes the bail away from the sheave resulting in the open front end of the bucket also being pushed away from the sheave to some extent. This reduces the likelihood of the front end of the bucket catching on the sheave.

In the second place, as the bucket proceeds from its dotted line position in Fig. 2 to its full line position in Fig. 3, the plate 20 bearing against the sheave functions as a fulcrum between the front and rear ends of the bail which performs as a lever. As the front end of this bail-lever is pulled upwardly by the cable the plate-fulcrum rocks upwardly against the sheave, whereby the rear end of the bail is swung downwardly to depress the front end of the bucket so that it will not catch on the sheave. By the time the front edge of the bucket is permitted to engage the sheave, such as shown in broken lines in Fig. 3, it is far enough around the sheave to avoid catching on it. As shown in Fig. 3 in broken lines, the right-hand plate 20 has been pulled out of contact with the sheave, and the front edge of the bucket has moved into the sheave far enough to engage it. The plates extend rearwardly on the bail a distance sufficient to hold it away from the sheave until there is no danger of the bucket catching on the sheave.

The positions of Fig. 4 illustrate the final movements of the bucket after it is safely past the point where it could catch on the sheave. In the full line position the outer surface of the bucket is in contact with the sheave and riding around it. In the dotted line position the bucket is free of the sewer pipe and has swung into a vertical position in the manhole from which it is hoisted and emptied.

According to the provisions of the patent statutes, we have explained the principle, preferred embodiment and mode of operation of our invention, and have illustrated and described what we now consider to represent its best embodiment. However, we desire to have it understood that, within the scope of the appended claims, the invention may be practiced other-

wise than as specifically illustrated and described.

We claim:

1. A sewer cleaner comprising a bucket, a bail pivotally connected to the bucket and adapted to be connected to a cable for dragging the bucket through a sewer and up around a sheave into a manhole, and a pair of plates each having its forward edge connected to the central portion of the bail and the outer ends of its rear edge adjoining the bail, said rear edge curving outwardly between said outer ends, and said plates being adapted to engage the sheave and push the bail away from it and to provide a fulcrum while the bail is circumventing the sheave, whereby upward pull of the cable causes the bail to rock like a lever on said fulcrum so that the rear end of the bail will depress the front end of the bucket and prevent it from catching on the sheave.
- 15 2. A sewer cleaner comprising a bucket, a bail pivotally connected to the bucket and adapted to be connected to a cable for dragging the bucket through a sewer and up around a sheave into a manhole, a pair of plates having their forward edges connected to opposite sides of the central portion of the bail, each plate having the outer ends of its forward and rear edges meeting at the bail, the rear edge of each plate curving outwardly between its ends, said plates being adapted to engage the sheave and push the bail away from it and to provide a fulcrum while the bail is circumventing the sheave, whereby upward pull of the cable causes the bail to rock like a lever on said fulcrum so that the rear end of the bail will depress the front end of the bucket and prevent it from catching on the sheave.
- 25 3. A sewer cleaner comprising a bucket, a bail pivotally connected to the bucket and adapted to be connected to a cable for dragging the bucket through a sewer and upwardly around a sheave into a manhole, a pair of rearwardly diverging plates each having its forward edge connected to the central portion of the bail and the outer ends of its rear edge adjoining the bail, said rear edge curving outwardly between said outer ends and the center line of each plate extending outwardly and rearwardly of the plane of the bail at substantially a 45° angle said plates being adapted to engage the sheave and push the bail away from it and to provide a fulcrum while the bail is circumventing the sheave whereby upward pull of the cable causes the bail to rock like a lever on said fulcrum so that the rear end of the bail will depress the front end of the bucket and prevent it from catching on the sheave.
- 30 4. A sewer cleaner comprising a bucket, a bail pivotally connected to the bucket and adapted to be connected to a cable for dragging the bucket through a sewer and upwardly around a sheave into a manhole, a pair of rearwardly diverging plates each having its forward edge connected to the central portion of the bail and the outer ends of its rear edge adjoining the bail, said rear edge curving outwardly between said outer ends and the center line of each plate extending outwardly and rearwardly of the plane of the bail at substantially a 45° angle said plates being adapted to engage the sheave and push the bail away from it and to provide a fulcrum while the bail is circumventing the sheave whereby upward pull of the cable causes the bail to rock like a lever on said fulcrum so that the rear end of the bail will depress the front end of the bucket and prevent it from catching on the sheave.
- 35 5. A sewer cleaner comprising a bucket, a bail pivotally connected to the bucket and adapted to be connected to a cable for dragging the bucket through a sewer and upwardly around a sheave into a manhole, a pair of rearwardly diverging plates each having its forward edge connected to the central portion of the bail and the outer ends of its rear edge adjoining the bail, said rear edge curving outwardly between said outer ends and the center line of each plate extending outwardly and rearwardly of the plane of the bail at substantially a 45° angle said plates being adapted to engage the sheave and push the bail away from it and to provide a fulcrum while the bail is circumventing the sheave whereby upward pull of the cable causes the bail to rock like a lever on said fulcrum so that the rear end of the bail will depress the front end of the bucket and prevent it from catching on the sheave.
- 40 6. A sewer cleaner comprising a bucket, a bail pivotally connected to the bucket and adapted to be connected to a cable for dragging the bucket through a sewer and upwardly around a sheave into a manhole, a pair of rearwardly diverging plates each having its forward edge connected to the central portion of the bail and the outer ends of its rear edge adjoining the bail, said rear edge curving outwardly between said outer ends and the center line of each plate extending outwardly and rearwardly of the plane of the bail at substantially a 45° angle said plates being adapted to engage the sheave and push the bail away from it and to provide a fulcrum while the bail is circumventing the sheave whereby upward pull of the cable causes the bail to rock like a lever on said fulcrum so that the rear end of the bail will depress the front end of the bucket and prevent it from catching on the sheave.
- 45 7. A sewer cleaner comprising a bucket, a bail pivotally connected to the bucket and adapted to be connected to a cable for dragging the bucket through a sewer and upwardly around a sheave into a manhole, a pair of rearwardly diverging plates each having its forward edge connected to the central portion of the bail and the outer ends of its rear edge adjoining the bail, said rear edge curving outwardly between said outer ends and the center line of each plate extending outwardly and rearwardly of the plane of the bail at substantially a 45° angle said plates being adapted to engage the sheave and push the bail away from it and to provide a fulcrum while the bail is circumventing the sheave whereby upward pull of the cable causes the bail to rock like a lever on said fulcrum so that the rear end of the bail will depress the front end of the bucket and prevent it from catching on the sheave.
- 50 8. A sewer cleaner comprising a bucket, a bail pivotally connected to the bucket and adapted to be connected to a cable for dragging the bucket through a sewer and upwardly around a sheave into a manhole, a pair of rearwardly diverging plates each having its forward edge connected to the central portion of the bail and the outer ends of its rear edge adjoining the bail, said rear edge curving outwardly between said outer ends and the center line of each plate extending outwardly and rearwardly of the plane of the bail at substantially a 45° angle said plates being adapted to engage the sheave and push the bail away from it and to provide a fulcrum while the bail is circumventing the sheave whereby upward pull of the cable causes the bail to rock like a lever on said fulcrum so that the rear end of the bail will depress the front end of the bucket and prevent it from catching on the sheave.
- 55 9. A sewer cleaner comprising a bucket, a bail pivotally connected to the bucket and adapted to be connected to a cable for dragging the bucket through a sewer and upwardly around a sheave into a manhole, a pair of rearwardly diverging plates each having its forward edge connected to the central portion of the bail and the outer ends of its rear edge adjoining the bail, said rear edge curving outwardly between said outer ends and the center line of each plate extending outwardly and rearwardly of the plane of the bail at substantially a 45° angle said plates being adapted to engage the sheave and push the bail away from it and to provide a fulcrum while the bail is circumventing the sheave whereby upward pull of the cable causes the bail to rock like a lever on said fulcrum so that the rear end of the bail will depress the front end of the bucket and prevent it from catching on the sheave.
